UNITED STATES PATENT OFFICE.

JOHN F. O'CONNOR, OF CHICAGO, ILLINOIS, ASSIGNOR, BY MESNE ASSIGNMENTS, TO
WILLIAM H. MINER, OF CHICAGO, ILLINOIS.

ROLLER SIDE BEARING FOR RAILWAY-CARS.

972,902.

Specification of Letters Patent. Patented Oct. 18, 1910.

Application filed October 1, 1909. Serial No. 520,554.

To all whom it may concern:

Be it known that I, JOHN F. O'CONNOR, a citizen of the United States, residing in Chicago, in the county of Cook and State of Illinois, have invented a new and useful Improvement in Roller Side Bearings for Railway-Cars, of which the following is a specification.

My invention relates to improvements in roller side bearings for railway cars.

In the accompanying drawing forming a part of this specification, Figure 1 is a front elevation of truck and body bolsters of a railway car having roller side bearings embodying my invention. Fig. 2 is a central, vertical longitudinal section of my improved side bearing taken on the line 2—2 of Fig. 3. Fig. 3 is a plan view. Fig. 4 is a vertical section on line 4—4 of Fig. 3. Fig. 5 is a detail perspective view of one of the roller spacers.

In the drawing, A represents the truck bolster, A¹ the body bolster of a railway car. B is the base or lower bearing plate of my roller side bearing, the same being secured to the truck bolster A. It is provided with a reversely inclined or double cone-faced tread b to receive the double cone or oppositely beveled anti-friction rollers C C, the tread b being curved about the king bolt as a center, as will be readily understood from Fig. 3 of the drawing. The lower bearing plate B is further provided on each side of the tread b with upwardly projecting flanges or wings b¹, provided at the upper portion with overhanging shoulders or guides b² for interengagement with the corresponding guides d d¹ of the upper or movable bearing plate D, which contacts with the body bolster A¹ or to wearing plates A² secured thereto. The upper or movable bearing plate D has depending sides d², one of which is furnished with an integral guide d for engagement with the guide b² of the lower bearing plate B, and the other of which is provided with a longitudinal groove to receive a removable guide d¹ which engages the corresponding guides b² of the lower bearing plate B, thus removably securing the upper and lower bearing plates together, while permitting the upper bearing plate to reciprocate in respect to the lower one. The upper bearing plate D has depending or downwardly curved end portions d³ which partially over-

hang or house the anti-friction roller C. The upper or movable bearing plate D is furnished with a reversely inclined or double cone-faced tread d⁴ for the anti-friction rollers C C to roll against.

To keep the anti-friction rollers C C properly spaced and to cause them and the upper bearing plate to automatically return to central or normal position after each swinging movement of the body and truck bolsters about the king bolt in respect to each other when the pressure or weight on the side bearing is again relieved, I provide the side bearing with a pair of spacers F, each having a pair of studs f to enter the hole C¹ in the anti-friction roller C, one of these spacers F fitting on each side of the rollers and between the ends of the rollers and the upwardly projecting flanges or wings b¹ of the lower bearing plate B. The upper bearing plate D also has central guides or shoulders d⁵ against which the upper portions of the spacers F may engage on their inner faces. The spacers F are provided with upwardly projecting shoulders or lugs f² to engage the followers G which fit in a central chamber or recess D¹ with which the upper bearing plate is provided, and abut against shoulders d⁶ on said bearing plate. A coiled spring H is interposed between the followers G bearing at one end against one follower and at the opposite end against the other, the spring and the followers being supported in position by a guide stem g which is preferably curved about the king bolt as a center, and fits at its end in suitable slots d⁷ in the upper bearing plate D. As the movement of the upper bearing plate D in either direction is twice that of the axes of the rollers C in the same direction, the spring H is compressed at each movement so that it tends to restore the parts to their central and normal position as soon as the pressure or weight is relieved from the side bearing. As the roller treads of the bearing plates are curved about the king bolt as a center, the oppositely beveled or double cone anti-friction rollers C are made correspondingly larger at their outer ends than their inner ends.

I claim:

1. In a roller side bearing, the combination with a lower bearing plate, of an upper bearing plate, anti-friction rollers inter-

posed between said bearing plates, a pair of separate and independently movable spacers one at each end of the rollers and each having studs fitting in the ends of the anti-friction rollers and provided with shoulders for followers to bear against, said upper bearing plate having a recess to receive a spring, and shoulders for followers to engage, and a spring and followers, substantially as specified.

2. In a roller side bearing, the combination with a lower bearing plate, of an upper bearing plate, anti-friction rollers interposed between said bearing plates, a pair of
15 spacers having studs fitting in the ends of the anti-friction rollers and provided with shoulders for followers to bear against, said upper bearing plate having a recess to receive a spring, and shoulders for followers
20 to engage and a spring and followers, said upper and lower bearing plates having oppositely inclined or double cone-faced treads, and said anti-friction rollers being of double cone form, substantially as specified.

8. In a roller side bearing, the combination with a lower bearing plate, of an upper bearing plate, anti-friction rollers interposed between said bearing plates, a pair of
30 spacers having studs fitting in the ends of the anti-friction rollers and provided with shoulders for followers to bear against, said upper bearing plate having a recess to receive a spring and shoulders for followers
35 to engage, and a spring and followers, said lower bearing member having upright wings furnished with guide shoulders and said

upper bearing plate having depending sides furnished with guides engaging said guide shoulders on the lower bearing plate, substantially as specified. 40

4. In a roller side bearing, the combination with a lower bearing plate, of an upper bearing plate, anti-friction rollers interposed between said bearing plates, a pair of spacers having studs fitting in the ends of the anti-friction rollers and provided with shoulders for followers to bear against, said upper bearing plate having a recess to receive a spring and shoulders for followers 50 shoulders for followers to bear against, said lower bearing member having upright wings furnished with guide shoulders, and said upper bearing plate having depending sides furnished with guides engaging said guide 55 shoulders on the lower bearing plate, one of said last mentioned guides being in a separate piece and removable, substantially as specified.

5. In an anti-friction side bearing, the combination with a lower bearing plate, of an upper movable bearing plate, anti-friction rollers between said bearing plates, separate and independently movable spacers one at each end of the rollers and each having studs fitting in the ends of the rollers, a spring and followers, said upper bearing plate and said spacers having stop shoulders to engage the followers, substantially as specified. 60 65
